MESNE ASSIGNMENTS, TO FIRST TRUST AND SAVINGS BANK, TRUSTEE, OF CHI-
CAGO, ILLINOIS.

AUTOMATIC EXTENSION TELEPHONE SYSTEM.

1,151,547.

Specification of Letters Patent. Patented Aug. 24, 1915.

Application filed December 20, 1906. Serial No. 348,752.

To all whom it may concern:

Be it known that we, TALEBOT G. MARTIN and FRITZ LUBBERGER, both citizens of the United States of America, and residents of Chicago, Cook county, Illinois, have invented a certain new and useful Improvement in Automatic Extension Telephone Systems, of which the following is a specification.

10 Our invention relates to automatic telephone exchange systems in which a telephone line is provided with a master telephone and one or more extension telephones.

An automatic telephone extension or party line lock-out arrangement is disclosed in application Serial No. 292,188.

An object of our present invention, which is subordinate to said prior application, is to provide an improved and highly efficient 20 lock-out arrangement for the extension lines of an automatic telephone system.

Another object is to provide certain novel features and details of construction and combinations which will permit intercommunication between the extension subscribers, as well as between the extension subscribers and the main or master telephone operator, and which will in various other ways increase the efficiency and improve the service 30 of a system of this particular character.

To the foregoing and other useful ends, our invention consists in matters hereinafter set forth and claimed.

In the accompanying drawings, Figure 1 is a top plan view of the lock-out switch with the cover removed. Fig. 2 is a side elevation of the switch. Fig. 3 is a top plan view of a portion of the lock-out switch, showing a number of the relays, and also 40 showing the switch in use. Fig. 4 is an end view of the lock-out switch, with the cover in place. Fig. 5 is a diagram showing the general circuit connections for the accommodation of six party line or extension stations Nos. 1, 2, 3, 4, 5 and 6. Fig. 6 shows diagrammatically the lock-out switch and one extension telephone A and the master telephone F. Figs. 6 and 7 taken together show diagrammatically the substation D 45 connected with a first-selector E, connector C, and first-selector H of the called line leading to the lock-out switch shown in Fig. 6.

In Fig. 7 the ringer generator is shown at I and the busy signaling apparatus at J. 55 The battery B' for the lock-out box, as shown in Figs. 5 and 6, is preferably composed of fourteen common dry cells. The storage battery B or other source of current shown in Fig. 7, having its positive terminal 60 preferably grounded at G, may be of any voltage suitable for operating the central station apparatus. The substations may be of any suitable or approved type, for example, of the general type shown in Patent 65 No. 1,101,853, issued June 30, 1914. The substation comprises the usual receiver 2, switch-hook 3, induction-coil 4 consisting of the primary winding 5 and secondary winding 6, transmitter 7, local battery 8 and 70 ringer 9.

In addition to the above mentioned parts the substation is provided with an impulse wheel 10 which has the usual vertical impulse teeth 11, which latter are adapted to 75 operate the vertical impulse spring 12. The impulse wheel carries the rotary impulse tooth 13 which operates the rotary impulse spring 14. The switch-hook has radiating from its body a number of cam arms 15, 16 80 and 17, and is pivotally secured to the keyboard (not shown) by the screw 18 about which it moves. The movement is produced by a spring not shown, and the switch-hook is operated for the purpose of changing certain circuit connections to be disclosed. The cam arm 15 controls the so-called locking arm 19 that normally rests in the position shown at substation A. After the dial is rotated the locking arm 19 occupies the position shown at substation D, and the cooperating ground springs 20 and 21 engage, thus placing the ground post 22 in contact with the substation ground G'. When the subscriber releases the dial after rotating it, as 90 described, the vertical impulse teeth 11 will cause the vertical impulse spring 12 to come into contact with the ground post 22, and immediately after, the rotary impulse tooth 13 causes the rotary impulse spring 14 to 100 come in contact with the same ground post 22, and thus ground impulses are delivered to the line conductors. When the switch-hook is down, the cam arm 17 maintains a contact with the spring 23, thereby bridging 105 the ringer 9 across the line. The springs 24

and 25, and 26 and 27 are then disengaged, and the primary circuit, including the winding 5 in series with the transmitter 7 and local battery 8, is interrupted by the separation of the springs 26 and 27. The disengagement of the springs 24 and 25 removes the secondary winding 6 and the receiver 2 from across the line. The signaling device whereby a subscriber may signal another, 10 after a connection has been established, comprises a push-button 28 and a spring 29, which latter normally engages the contact point 30; but when the push-button 28 is pressed, the spring 29 leaves the contact point 30 and engages the contact point 31, which latter is connected with the substation ground G'. Means whereby the subscriber may release the central station apparatus brought into service comprises three springs 20 32, 33 and 34 known as the release springs, and so controlled by the cam arm 16 that when the switch-hook descends the three release springs are brought into contact, thereby grounding both of the subscriber's line 25 conductors simultaneously. Furthermore, the substations connected with the lock-out box, as shown at A in Fig. 6, for instance, have in addition to the above-mentioned parts the ground-closing springs 35 and 36 controlled 30 by the cam arm 37'. At each substation A there is also provided a buzzer 38 by which the operator at the master telephone F signals a subscriber at the extension telephone.

35 The first-selector shown at E may be of any suitable or approved type, for instance of the general type described in Patent No. 815,321, granted March 13, 1906, to Keith, Erickson and Erickson. Among other details it 40 embodies the following well-known devices and circuits: A switch-shaft (not shown) carries the vertical and rotary wipers 39 and 40, respectively, and the private wiper 41 and the side switch, which is well known, and 45 which comprises the side switch wipers 42, 43, 44 and 45, known as the vertical, rotary and private side switch wipers, and the rotary magnet side switch wiper, respectively. The side switch is under the control of the private magnet 46, and through the medium of the vertical line relay 47, and while the side switch is in first position, the subscriber controls the vertical magnet 48, which latter operates to raise the shaft and shaft wipers 39, 50 40 and 41 vertically. By means of the rotary line relay 49, and while the side switch is in first or second position, the subscriber controls the private magnet 46 and, therefore, the side switch. While the side switch 55 is in second position the rotary magnet 50, which carries the shaft and shaft wipers in a rotary or circular direction, is energized. The vertical and rotary line relays 47 and 49, acting conjointly, provide means whereby 60 the subscriber controls the release magnet 51 while the side switch is in the first or second position. After the side switch passes to third position, and since the first-selector is of the trunk-release type, the side switch is controlled through the next switch with 70 which a connection has been established, by way of the private wiper 41 and by means of the back-release relay 52. The bridge-cut-off relay 53 is provided to open the connection between the line relays 47 and 49 75 and between said relays and battery B. This is desirable because if the relays are not disconnected from each other and the battery when the selector is called, the ringing current for signaling the subscriber may 80 then operate either or both of the relays 47 and 49 and cause some interference with the connection. It is also desirable to remove the bridge formed through the said relays from across the line to give the voice-currents as clear a path as possible. The first-selector switch-shaft is also provided with a normal post arm 54, which, when the shaft is in normal position, closes the spring 55 in 85 contact with the contact point 56; but when the shaft is raised one or more steps the spring 55 closes in contact with the contact point 57. The connector switch C may also be of any suitable or approved type, for instance of the type described in Patent No. 95 815,176, granted March 13, 1906, to Keith, Erickson and Erickson. The mechanical details of the first-selector and connector, as is well known, are very much the same, although there is some material difference 100 in the circuits. The connector switch-shaft (not shown), like the first-selector switch-shaft, carries the line wipers 58 and 59 and the private wiper 60. The connector switch is also controlled by the calling subscriber through the medium of the vertical and rotary line relays 61 and 62. The vertical line relay 61 directly controls the vertical magnet 63 and also the rotary magnet 64 and ringer relay 65. The office of the vertical magnet 105 63 is to give the shaft and shaft wipers their vertical motion, and the rotary magnet 64 imparts to the shaft and shaft wipers a rotary or circular motion. The rotary line relay 62 controls the private magnet 66, 110 which latter under certain conditions in turn controls the vertical and rotary magnets 63 and 64, the release magnet 67, and also the side switch wipers 68, 69, 70 and 71. The side switch of the connector, like the side 115 switch of the first-selector, has a normal or first position, a second position and a third position. The release magnet 67 is also controlled by the line relays 61 and 62 jointly. By the condensers 72 and 73 the 120 main line circuit passing through the connector is divided into two sections. The back-bridge relays 74 and 75 give the called subscriber means whereby he may release the connector switch which has been con-

nected with his line. The central office is equipped with a busy signaling apparatus J of any suitable design, as, for example, the one comprising an interrupter 76 in series 5 with the primary winding 77 of the induction-coil 78, whereby a busy signaling current is induced in the secondary winding 79 of the said coil. The secondary winding 79 is connected to the contact point 80, as 10 shown. The connector switch-shaft also carries a normal post arm 81 which, when the connector shaft is off normal, allows the spring 82 to engage the contact point 80, thus closing the busy signaling circuit.

15 The first-selector H of the called line is the same as the first-selector E of the calling line, and, therefore, the description of selector E is applicable to selector H.

The substation F is similar to substation 20 D and requires no further description.

The lock-out switch herein disclosed is of such a nature that a variety of combinations of connections may be secured between telephones by its use. In fact, owing to its im- 25 proved character the same service may be had as by the use of a private branch exchange. For instance, a party line subscriber to the lock-out switch may call to the main exchange without any assistance 30 from the master telephone subscriber. He operates his dial in the well-known manner for each digit of the desired number. When the calling subscriber turns the dial for the first digit all other party line subscribers, 35 except the master telephone subscriber, are automatically locked out, and upon replacing the receiver to the switch-hook the lock-out switch is restored. Any subscriber allotted to the lock-out switch may be placed 40 in communication with any other local subscriber thereto by removing his receiver and pressing the signaling button, thus signaling the master telephone station. The attendant at the main telephone upon learning 45 which local line station is desired simultaneously presses two lock-in buttons, one allotted to the calling substation and the other to the desired substation, thus locking-in both substations on the same line to the 50 exclusion of all other local subscribers. The attendant at the main telephone now presses a signaling button for signaling the desired substation. Either subscriber, upon restoring his receiver to the switch-hook, releases 55 the lock-out switch mechanism. Said lock-out switch is provided with the locking-in relays 83, 84, 85, 86, 87 and 88, one of which is allotted to each party line or extension telephone connected with the lock-out switch, 60 and through the medium of which the allotted subscriber is locked in or out by the lock-in bar hereinafter described. Each lock-in relay, therefore, performs the same function for its individual line, and what 65 is true of the lock-in relay 83 is true of the relays 84, 85, 86, 87 and 88. The lock-in relay 83, for instance, controls a set of springs 89, 90, 91, 92, 93 and 94, a similar set of which is under the control of each lock-in relay. Each relay armature, like the 70 armature 95 of the relay 83, is provided with a semaphore arm 96, which latter is normally maintained with reference to the aperture 97 in the position shown at K, Fig. 3; but when the lock-in relay 83 becomes energized and pulls the armature 95 down, the arm 96 takes the position shown at L, and a visual signal appears at the aperture 97 of the lock-out switch cover. The lock-in magnet 98, which energizes together with 75 any one of the lock-in relays, operates the lock-in bar 99 to which reference has already been made. Referring to Fig. 3, suppose the relay 86 to become energized and its armature to shift the springs to the position 80 shown; the lock-in magnet 98 energizes simultaneously and the lock-in bar is operated, locking out the armature 95 of the relay 85—that is, locking it in its normal position, and the armature of 85 relay 86 is locked in its attracted or operated position. In said Fig. 3, at a, b, and c are shown, respectively, the relative positions of a locking-in relay armature and the lock-in bar lever arm when viewed from the 90 direction indicated by the arrows. At a the armature is shown in a locked-out position—that is, the armature is locked in its normal position, as the armature 95 above; at b is shown the armature and lever arm in normal 95 position, these parts being shown in Fig. 1; at c is shown the lock-in bar lever arm locking the relay armature in its attracted or operated position, as the armature of relay 86 in Fig. 3. When the energizing current 100 ceases to flow through the lock-in magnet 98, the lock-in bar is retained in its operated position by the release armature 100 engaging the lever arm 101 of the lock-in bar. Furthermore, the operation of the lock-in 105 bar 99 closes the springs 102 and 103 in contact (Fig. 5), and breaks the engagement of the springs 104 and 105, 106 and 107, and 108 and 109. The release magnet armature 100 is shown in its normal position in Figs. 1 110 and 5, and in Fig. 3 it is shown in its operated position. The projecting shoulder 110 near the end of the armature has engaged the lever arm 101, while the lock-in 115 bar 99 permits the springs 111 and 112 to 120 disengage. The said lock-in bar remains in this position, thus locking the armature of relay 86 in its operated position and locking the armature of relay 85 in its normal position. The release magnet 113 upon energizing attracts the armature 100 and draws the shoulder 110 away from the lever arm 101, thus permitting the lock-in bar 99 to resume its normal position.

The lock-in bar 99 is pivotally secured by 125

the pivot points 114 and 115, which latter are mounted in the ears 116 and 117, respectively, of the base or mounting frame 118. The lock-in bar 99 is an L-shaped member on one web of which is placed an adjusting screw 119, by means of which the angle through which said bar operates may be regulated. This web also controls the contact springs 102 and 103, 104 and 105, 106 and 107, and 108 and 109. On the other web of the lock-in bar are mounted the lever arms 120, 121, 122, 123, 124 and 125, which latter when the bar 99 is operated retain the lock-in relay armatures in a locked position. The lock-in relays 83, 84, 85, 86, 87 and 88 are rigidly secured to a web 126 formed at a right-angle to the base 118. The release relay 127 is controlled from the substations Nos. 1, 2, 3, 4, 5, and 6 and operates, when energized, to place the springs 128 and 129 in contact, which springs in turn close an energizing circuit through the release magnet 113, providing the lock-in bar has operated and closed the springs 102 and 103 in contact. The differentially-wound buzzer relay 130 is provided, whereby a party line subscriber may, by pressing his signaling button and thus grounding his vertical line conductor, signal the operator at the master telephone when he wishes a connection with the operator, or when he wishes to be connected with one of the extension subscribers. The subscriber, by grounding his vertical line, closes an energizing circuit through the winding 131 of the coil 130 (Fig. 5). The armature 132 is attracted, thereby opening the contact between the springs 133 and 134, which in turn opens the energizing circuit through the winding 131; hence the coil becomes deenergized and the armature 132 returns to its normal position, and the springs 133 and 134 again engage, and again the energizing circuit through the winding 131 is closed, providing the vertical line is still grounded. The alternate energization and deenergization of the relay 130 causes the armature 132 to chatter or buzz, which is understood by the master telephone operator to be his signal. In normal position the key 135 maintains the master telephone in connection with the party line telephones, as shown in Fig. 5; but when shifted, as shown in Fig. 6, the master telephone is connected to the trunk line that connects the central exchange with the subexchange or lock-out switch. The normal position is used by the master telephone attendant to communicate with the local subscribers, and the shifted position to connect with the trunk line. A second key 136 is provided, whereby the supervising subscriber or operator may, in case of emergency, release an established connection, or while two local subscribers are being connected the key 136

is depressed to prevent interference. To release the lock-out switch mechanism the springs 137 and 138 are forced together to close an energizing circuit through the release magnet 113 when the lock-in bar 99 is in an operated position, and the springs 102 and 103 are in contact; and to prevent interference the springs 209 and 210 separate, destroying the energizing circuit for each and every lock-in relay. Furthermore, the lock-out switch is equipped with lock-in push-buttons 139 and with signaling push-buttons 140, one of each being provided for each extension line having connection with the lock-out switch. If the master telephone receives a call from outside for a connection with substation #1, for example, it becomes necessary to lock the said substation onto the main trunk. This is done by means of the former button 139. This latter is pressed once and the supervising subscriber thus energizes the lock-in relay 83 and lock-in magnet 98, thereby locking in substation #1 on the main trunk line. The master telephone subscriber, by operating the key 135, as shown in Fig. 6, may bridge his telephone across the line. Of course, the attendant at the master telephone must signal the desired substation #1 by energizing the buzzer 38. This is done by means of the push-button 140 which the supervisory subscriber or operator presses (Fig. 6). The signal for the substation #1 comes to the lock-out switch, which is suitably equipped with a ringer 141 arranged across the trunk line. The said ringer 141, as shown, is connected in series with the condenser 142, and the said bridging circuit is normally closed between the springs 104 and 105. It will be noticed by referring to Figs. 5 and 6 that when the key 135 is thrown, the master telephone is connected with the trunk line through the switch springs 106 and 107, and 108 and 109 that short-circuit the condensers 143 and 144. In order that the master operator may be able to make a call these springs must be in contact. When the outside and inside subscribers are connected, as explained, the said springs are separated, but across the springs 106 and 107, and 108 and 109 are bridged the condensers 143 and 144, respectively; and it will be seen that by the use of the said condensers the supervisory operator may still bridge the master telephone F across the trunk line and listen through said condensers, even after the lock-in bar 99 has operated and opened the contact between the springs 106 and 107, and 108 and 109.

From the foregoing it will be evident that a number of substations are afforded access to a line of two conductors connected with a central office and terminating in a first-selector, such as the first-selector H. Such a line is given one number and any sub-

scriber desiring to communicate with any one of the subscribers of the said line calls in the ordinary way and completes the connection. The signal is received by the operator, who inquires which substation is desired, and being informed presses a signaling button corresponding to the desired substation, said button energizing a buzzer at the called substation. The operator at the master telephone then presses the button 139, if substation A is wanted, which locks in subscriber A on the trunk line, and at the same time locks out of service for the time being all of the other extension subscribers' 15 telephones. The operation of the lock-out switch may be understood more clearly from its action when an outside subscriber calls to the master telephone subscriber and is given a connection with one of the local subscribers. Assume, therefore, that the lock-out switch line is #220 and that the subscriber D at substation #120 (Fig. 7) wishes to communicate with a subscriber A of the line #220 in question.

25 The first digit being 2, the subscriber at substation #120 turns his dial for the first digit 2, thereby grounding the vertical line conductor 145 twice and the rotary line conductor 146 once upon the return motion of 30 the dial. The ground post 22 is placed in connection with the substation ground G', in a well known manner, by the action of the locking dog 147. Grounding the vertical line conductor 145 energizes the vertical line 35 relay 47 of the first-selector. The circuit through the said relay extends from substation ground G', ground post 22, vertical impulse spring 12, vertical line conductor 145, side switch wiper 42, contact point 148 to 40 the relay 47, through the bridge-cut-off springs 149 and 150 to the battery lead 151, thence through battery B and to ground G. Each time the vertical line relay 47 is energized, the springs 152 and 153 are pressed 45 into engagement and an energizing circuit is established each time through the vertical magnet 48. The circuit through the said magnet extends from ground G' to the springs 152 and 153, to the private magnet 50, 50 springs 154 and 155, vertical magnet 48 to the battery lead 151, thence through battery B and to ground G. The vertical magnet being operated twice, the first-selector switch-shaft and wipers 39, 40 and 41 are 55 carried to a level with the contact points that constitute the terminals of the trunk line leading to the connector C. Following the vertical impulses the rotary impulse spring comes into contact with the ground 60 post 22, thereby grounding the rotary line conductor 146 once and energizing the rotary line relay 49 of the first-selector once. The path of the energizing current may be traced as follows: from the substation ground G' to the rotary line conductor 146, side switch wiper 43, contact point 156 to the rotary line relay 49, bridge-cut-off springs 157, 149 and 150 to the battery lead 151, thence through battery B and to ground G. The rotary line relay 49 upon energizing 70 closes the springs 158 and 152 in contact, thereby closing an energizing circuit through the private magnet 46 which extends from ground G' to the springs 152 and 158, private magnet 46 to the battery lead 151, thence through battery B and to ground G. The private magnet 46 being energized for a moment, the side switch of the first-selector E passes from first to second position, thereby permitting the side 75 switch wiper 45 to engage the contact point 159, thus closing a circuit through the rotary magnet 50. The current-flow is from ground G' to the contact point 159, side switch wiper 45, through one coil of the rotary magnet to the interrupter springs 160 and 161, through the winding of the second coil of the rotary magnet 50, thence to the battery lead 151, and through battery B and to ground G. The rotary magnet is energized one step and the shaft wipers 39, 40 and 41 are carried into engagement with the bank contacts that constitute the terminal 80 of the trunk line leading to the connector switch C, assuming that the trunk leading 85 to the said connector leads off from the second set of contacts of the first level; but if the first trunk line is busy an energizing circuit is established through the private magnet 46, when the private wiper 41 strikes the 90 grounded private bank contact, thereby retaining the side switch in second position and maintaining the energizing circuit through the rotary magnet 50. The rotary magnet, by intermittent energization, thus 95 causes the shaft to rotate step-by-step and carry the wipers past the last busy trunk line. However, as soon as the private magnet is deenergized the side switch is tripped into third position; but if there are no busy 100 contacts to be passed over, as assumed in the first instance, the rotary magnet 50, as is well known, trips the side switch to the 105 third position, with the result that the side switch wipers 42, 43, 44 and 45 engage their 110 respective contact points 162, 163, 164 and 165, thus extending the subscriber's line conductors 145 and 146 to the connector C. Also, since the side switch wiper 44 engages the ground contact point 161, a guarding 115 potential is established at the private wiper 41 for protecting the seized trunk line from being molested by any other switch.

The second digit is called after the subscriber has established connection with the 120 connector C by way of the trunk conductors 166 and 167. The subscriber rotates the dial, as described, for the second digit 2, thereby 125 grounding the vertical and rotary line conductors 145 and 146, which causes the ener-

- gization of the connector vertical and rotary line relays 61 and 62. The current for energizing the vertical relay 61 flows over the following path: from ground G' to the vertical impulse spring 12, vertical line conductor 145, side switch wiper 42, contact point 162, shaft wiper 39, trunk conductor 166, vertical relay 61 to the battery lead 151, thence through battery B and to ground G.
- 5 Each time that the vertical line relay 61 is energized the line relay springs 168 and 169 are pressed into contact, thereby closing an energizing circuit through the vertical magnet 63 over the following path: from ground G' to the springs 169 and 168, private magnet springs 170 and 171, side switch wiper 71, contact point 172, vertical magnet 63 to the battery lead 151, thence through battery B and to ground G. Each time that
- 10 the vertical magnet is energized it operates to raise the shaft and shaft wipers one step until said wipers are carried two steps to the level in which is located the terminal of the line #220. When the rotary line conductor
- 15 146 is grounded the rotary line relay 62 becomes energized through the following path: from ground G' to the rotary impulse spring 14, rotary line conductor 146, side switch wiper 43, contact point 163,
- 20 shaft wiper 40, trunk conductor 167, rotary line relay 62 to the battery lead 151, thence through battery B and to ground G. The energization of the said relay causes the energization of the private magnet 66 over
- 25 a circuit extending from ground G', springs 169 and 173, private magnet 66 to the battery lead 151, thence through battery B and to ground G, and the release of the side switch from first to second position, thus
- 30 placing the wipers 68, 69, 70 and 71 in connection with their respective contact points in the second position.
- The last digit being 0 the subscriber operates the dial as previously described, 45 grounding the vertical line conductor 145 ten times and the rotary line conductor 146 once. The vertical and rotary line relays 61 and 62 are operated over previously traced circuits. However, when the line
- 50 relay springs 168 and 169 engage, a circuit is then closed through the rotary magnet 64 instead of through the vertical magnet 63. The energizing circuit extends from ground G' to the springs 169 and 168, private magnet springs 170 and 171, side switch wiper 71, contact point 174, rotary magnet 64 to the battery lead 151, thence through battery B and to ground G. Each time that the
- 55 rotary magnet is energized it rotates the shaft and shaft wipers 58, 59 and 60 one step until the said wipers are carried into engagement with the normal conductors 175, 176 and 177 that lead to the selector H of the desired subscriber. The energization of
- 60 the rotary line relay 62, as previously stated, completes an energizing circuit through the private magnet 66 which now operates with one of two results, namely the release of the side switch from the second to third position, or the so-called busy release of the
- 65 connector, which will be described. Suppose the former result to occur and the side switch to pass to third position, thus placing the side switch wipers 68, 69, 70 and 71 in contact with the respective contact points
- 70 in the third position. Then when the side switch passes to third position a guarding potential is established for protecting the called line. This potential extends from ground G' to the contact point 178, side
- 75 switch wiper 70 to the shaft wiper 60 which engages the private contact of the called line. The said guarding potential also closes an energizing circuit through the bridge-cut-off relay 179 of the first-selector H, thereby removing the bridge formed by the vertical and rotary line relays of the first-selector H.
- To signal the called subscriber the calling subscriber presses the signaling button 28, placing the spring 29 in contact with the substation ground G', thereby energizing the vertical line relay 61. The path of the energizing circuit extends from ground G', contact point 31, spring 29, springs 24 and
- 80 25 to the vertical line conductor 145, side switch wiper 42, contact point 162, first-selector shaft wiper 39, trunk conductor 166, vertical relay 61 to the battery lead 151, thence through battery B and to ground G.
- 85 It will be remembered that the connector side switch has passed from second to third position, and that the side switch wiper 71 is in engagement with the contact point 180, thereby placing the vertical line relay 105 61 in control of the ringer relay 65 in the same manner in which the rotary magnet 64 came under the control of the vertical line relay 61 when the side switch passed from first to second position. Therefore, when the vertical line relay 61 presses the springs 168 and 169 into contact the ringer relay 65 is energized by a flow of current from ground G' to the relay springs 169 and 168, private magnet springs 170 and 171, side
- 90 switch wiper 71, contact point 180 to the ringer relay 65 and to the battery lead 151, thence through battery B and to ground G. The ringer relay upon energizing shifts the springs 181 and 182 from the springs 183 and 184 and onto the springs 185 and 185', respectively. This results in separating the calling subscriber's line from the called subscriber's line, and bridging across the line of the latter terminals of the ringer generator I. A signaling current is, therefore, sent from the generator I to the ringer relay springs 185' and 182, side switch wiper 69, connector shaft wiper 59, normal conductor 176, rotary line conductor
- 95 100 105 110 115 120 125 130

187 to the condenser 142, to the ringer 141, springs 104 and 105 to the vertical line conductor 186, normal conductor 175, connector shaft wiper 58, side switch wiper 68, ringer relay springs 181 and 185 back to the generator I. As soon as the calling subscriber ceases to press the signaling button 28 the ringer relay 65 becomes deenergized and the springs 181 and 182 resume their normal position in contact with the springs 183 and 184, respectively. When the ringer 141 sounds, the supervisory subscriber or operator throws the key 135 to the position indicated in Fig. 6, thus connecting the master telephone to the trunk line over the following path: from the vertical trunk line conductor 186 to the springs 188 and 189, condenser 144, vertical line conductor 190, through the springs 191 and 192, spring 193, winding 194 of the induction-coil 195, through the receiver 196, thence to the rotary line conductor 197 through the condenser 143, springs 198 and 199 to the rotary trunk line conductor 187. The operator having ascertained from the calling subscriber that the substation #1 is desired now throws the listening key 135 to the normal position, which operation bridges the master telephone across the multiple line terminals of all of the extension substations. Among these terminals are the terminals 90 and 93 of the substation #1 which are controlled by the locking relay 83; but substation #1 being desired, the operator now presses the calling button 140, which closes an energizing circuit through the buzzer or bell 38 of the substation #1. The circuit extends from ground G^a at the buzzer 38 to the conductor 200, push-button springs 201 and 202 to the battery lead 203, thence through battery B' and to ground g'. When the subscriber A has answered, the operator presses the locking button 139, which closes an energizing circuit through the locking relay 83 and lock-in magnet 98. The energizing circuit is as follows: from ground G^a to the push-button springs 204 and 205, conductor 206 to the lock-in relay 83, lock-in magnet 98, springs 207 and 208, springs 209 and 210, release magnet springs 112 and 111 to the battery lead 203, and through battery B to ground G. The energization of the lock-in relay 83 causes the desired subscriber's line to be disconnected from the master telephone and placed in connection with the trunk line conductors 186 and 187. This new connection is brought about by the shifting of the springs 90 and 93 from in contact with the springs 89 and 92 to engagement with the springs 91 and 94. Simultaneous with the energization of the lock-in relay 83 the lock-in magnet 98 is energized, and the lock-in bar 99 (Fig. 3) is locked in its attracted position, as previously described, which bar locks the armature of the energized relay to hold the extension line in permanent connection for the time being with the main trunk line conductors 186 and 187, and which bar at the same time locks out all armatures of deenergized relays, preventing them from operating to establish a connection with said trunk line conductors. After locking in a called party on the trunk line the operator may listen-in by throwing the key 135, thus placing the springs 189 and 198 in contact with the springs 188 and 199. However, if it is desired that the operator should not be able to listen-in on conversation over the trunk line, the two condensers 143 and 144 may be disconnected. By referring to Fig. 6, it will be seen that when the condensers 143 and 144 are removed, and the lock-in bar 99 is in a locked position, the master telephone is disconnected from the listening key 135 at the springs 106 and 107, and 108 and 109. The two substations D and A are connected by a circuit extending from the receiver 2 of substation D to the secondary winding 6 of the induction-coil 4, contact point 30, spring 29, springs 24 and 25 to the vertical line conductor 145, side switch wiper 42, shaft wiper 39, trunk conductor 166, condenser 72, ringer relay springs 183 and 181, side switch wiper 68, shaft wiper 58, normal conductor 175, vertical trunk line conductor 186, conductor 211, springs 91 and 90 to the vertical conductor 212, springs 213 and 214, and spring 215, through the secondary winding 216, thence to the receiver 217 of substation A, rotary line conductor 218, springs 93 and 94, rotary trunk conductor 219 to the rotary trunk line conductor 187, rotary normal conductor 176 and shaft wiper 59, side switch wiper 69, ringer relay springs 182 and 184, condenser 73, rotary trunk conductor 167, shaft wiper 40, side switch wiper 43 and rotary line conductor 146 to the receiver 2 of substation D. After the conversation has been completed over the above-traced circuit, the front release occurs when the calling subscriber restores the receiver 2 to the switch-hook 3, thereby pressing into engagement for a moment the release springs 32, 33 and 34. The contact of the said release springs grounds the vertical and rotary line conductors 145 and 146 simultaneously from ground G^a to the release spring 34, thence through the springs 33 and 32 to the vertical and rotary line conductors, thereby energizing the line relays 61 and 62 of the connector, which carries the springs 223 and 224 into contact, energizing the relay 52 of the first-selector E in series with the release magnet 67 of the connector C. The path of the latter circuit extends from ground G^a to the contact point 164, side switch wiper 44, release relay 52, first-selector switch-shaft wiper 41, connector trunk-release springs 223 and 224, re-

lease magnet 67 to the battery lead 151, thence through battery B and to ground G. When the connector release magnet 67 is thus supplied with current it energizes, and 5 as a result the switch-shaft and side switch are restored to normal position, thus breaking the connection between the connector switch-shaft wipers 58, 59 and 60 and the normal conductors 175, 176 and 177. The 10 back-release relay 52 of the first-selector E being in the same circuit with the release magnet 67 energizes simultaneously with the latter, and presses the springs 225 and 226 into engagement, which in turn closes 15 an energizing circuit through the release magnet 51 of the first-selector E. This circuit extends from ground G¹⁰ through the release springs 225 and 226, through the winding of the release magnet 51 to the battery lead 151, thence through battery B and to ground G. All of the relays and magnets thus energized attract their respective armatures, and as soon as the substation release 20 springs 32, 33 and 34 separate and break the ground connection with the line conductors 145 and 146 they again deenergize. The calling subscriber thus restores all switching apparatus which he originally brought into use.

25 The lock-out switch mechanism is restored to normal condition when the called subscriber A hangs up the receiver 217, thus pressing the release springs 229, 230 and 231 into engagement, which causes an energizing current to pass through the release relay 127. This energizing circuit extends from grounds G⁷ through the winding of the release relay 127, conductor 232 to the release 30 springs 231, 230 and 229, where the current divides and passes in two paths, one path extending from the release spring 230 to the vertical line conductor 212, contact springs 90 and 91, conductor 211, vertical trunk line conductor 186, through the winding of the vertical relay of the selector H, thence through the bridge-cut-off springs of the bridge-cut-off relay 179 to the battery lead 151, thence through battery B and to ground G. The second path extends from 35 the release spring 229 to the rotary line conductor 218, springs 93 and 94, conductor 219, rotary trunk line conductor 187, through the winding of the rotary line relay of the selector H to the bridge-cut-off springs of the bridge-cut-off relay 179, and to battery lead 151, thence through battery B and to ground G. The energization of the release relay 127 closes an energizing circuit 40 through the release magnet 113. The release magnet 113 (Fig. 3) upon energizing attracts its armature 100, thus drawing the shoulder 110 away from the lever arm 101 and allowing the lock-in bar 99 to resume its normal position. The force which restores 45 the lock-in bar is supplied by the springs 102, 107, 109 and 105. The release armature 100 upon being attracted closes the springs 111 and 112 in contact, thus restoring the energizing circuits for the locking magnet 98 and the locking relays 83, 84, etc. 70 The armature of the relay 83 being now liberated, the springs 90 and 93 pass out of contact with springs 91 and 94 and into contact with springs 89 and 92, respectively, thus breaking the connection with the trunk 75 line and again establishing connection with the master telephone, restoring the lock-out switch mechanism to its normal position.

75 The back-release is provided in order that called subscribers may not remain helplessly tied up, so to speak, while the bridge-cut-off relay 179 is energized. Should the called subscriber desire to make an independent call before the calling subscriber releases, he may do so by breaking the established connection and securing control of the first-selector H. The subscriber A, by simply restoring the receiver 217 to the switch-hook 220, thus pressing into engagement the release springs 229, 230 and 231, 90 grounds the vertical and rotary trunk line conductors 186 and 187 simultaneously. As a result an energizing current will pass through the vertical back-bridge relay 74 and through the rotary back-bridge relay 95 95 73 of the connector C. The circuit through the vertical back-bridge relay extends from ground G⁷ (Fig. 6) through the release relay 127, release conductor 232, release springs 231 and 230 to the vertical line conductor 212, springs 90 and 91, vertical conductor 211, thence to the vertical trunk line conductor 186, normal conductor 175, connector shaft wiper 58, side switch wiper 68, ringer relay springs 181 and 183 to the back-bridge relay 74, to the battery lead 151, thence through battery B and to ground G. The energizing circuit of the back-bridge relay 75 extends from ground G⁷ through the release relay 127, release conductor 232, release 100 springs 231, 230 and 229 to the rotary line conductor 218, through the springs 93 and 94 and rotary conductor 219, thence to the rotary trunk line conductor 187 and rotary normal conductor 176, connector shaft 105 wiper 59, side switch wiper 69, ringer relay springs 182 and 184, through the winding of the relay 75 to the battery lead 151, thence to battery B and to ground G. The 110 back-bridge relays 74 and 75, upon energizing simultaneously, press into contact the back-release springs 227 and 228, which completes an energizing circuit to the release magnet 67 from ground G¹² through the release springs 227 and 228 to the release magnet 67, thence to battery lead 151, and through battery B to ground G. The release magnet is thus energized and the switch-shaft wipers 58, 59 and 60 and side switch are restored to normal position. The 115 120 125 130

energizing circuit through the bridge-cut-off relay 179 is broken when the shaft wiper 60 leaves the private bank contact; thus the connector switch C is released and the first-selector H is restored to the control of the line #220. By grounding the line conductors 145 and 146 the subscriber D may restore the first-selector E. The release of the first-selector E, in this case, is accomplished 5 in the same manner and over the same circuits as explained in connection with the front release. An energizing circuit having been established through the release relay 127, the release of the lock-out switch 10 mechanism occurs, as previously stated. The first-selector H and the lock-out switch now being in normal condition the subscriber A, desiring to call out on the line, removes the receiver 217 from the switch-hook 220, which latter on rising, through 15 the medium of the cam arm 37', closes the springs 35 and 36 in contact. The subscriber A now rotates the dial for the first digit, which act places the co-operating 20 ground springs 221 and 222 in contact, in a well-known manner, thus establishing an energizing circuit through the lock-in relay 83 and the lock-in magnet 98, before the dial begins to return to normal position. This 25 energizing circuit extends from the substation ground G^s to the ground springs 222 and 221, to the ground springs 35 and 36, to the lock-in conductor 233, through the winding of the relay 83 and winding of 30 the magnet 98, through the springs 207 and 208, releasing springs 209 and 210, through the release magnet springs 112 and 111 to the battery lead 203, thence through battery B and to ground G. The lock-in relay 35 and lock-in magnet 98, by reason of the said energizing current, operate with the previously described result, and the vertical and rotary conductors 212 and 218 are shifted 40 to the conductors 211 and 219 which lead 45 to the trunk line conductors 186 and 187. The substation #1 is, therefore, locked-in on the trunk line, and the remaining extension substations are locked out, as previously explained. The subscriber A's line conductors being thus connected to the trunk line, the impulses transmitted by the dial on its return pass out to the lines and to the exchange operating the selector H for the first 50 digit, as the subscriber at D operated the switch E. Of course, the subscriber, after allowing the dial to rotate to its normal position, operates it again, once for each succeeding digit, and thus establishes connection 55 with the desired line in the same manner in which substation D called the line #220. Assume, when the trunk line is thus engaged by a first-selector, that a second subscriber, #2, for example, tries to call to the central office; then, since subscriber #2 is locked out, his lock-in relay 84 will not 60 energize; therefore, when he presses the button 234, upon attempting to signal, the impulse will operate the buzzer relay 130 of the lock-out switch. The operator, hearing such signal and seeing the semaphore of station 70 #1 in the busy position, informs the second subscriber that the trunk line is engaged. The current through the buzzer in this case flows from substation ground G^s through the springs 222 and 221 to the contact 235, 75 spring 215 to the vertical conductor 212, spring 90, contact point 89, winding 131 of the buzzer relay 130 to the contact point 133, armature 134 to the battery lead 203 and through battery B' to ground g'. When informed that the line is busy the subscriber, of course, hangs up his receiver; but he will, in so doing, ground both sides of his line. In this connection it will be noticed that the buzzer relay 130 is given two windings 80 85 which are differentially related when connected in multiple. Grounding the vertical side of the line when the switch-hook passes down will, therefore, not energize the buzzer, because the rotary side is grounded also, 90 and thus a false signal to the master telephone is prevented. When the receiver 217 of the first subscriber is restored to the switch-hook 220, after he has made his call, the release of the established connection and 95 the restoration of the lock-out switch mechanism to its operative condition is brought about. It will be understood that in this system when a called line is busy there is established a guarding potential at the connector private bank contacts of the desired line. Therefore, as has already been suggested, when the calling subscriber grounds his rotary line conductor at the end of the 100 last digit, the connector switch will be released, instead of the side switch passing to third position, as in the case where substation D called #220.

The busy release of the connector C, therefore, follows as a result of the energization of the rotary line relay 62, if the called line #220 is busy, as follows: The said relay 62, upon energizing, energizes the private magnet 66, as previously described, which in turn presses the springs 227' and 228' into contact. As soon as the said springs 227' and 228 engage, the release magnet 67 is then placed in connection with the private wiper 60 (since the side switch wiper 70 is now in second position), which 110 115 wiper 60 has been previously rotated onto a grounded contact. As a result a flow of current is sent through the release magnet 67 from the grounded private wiper 60 to the side switch wiper 70, to the private magnet springs 228' and 227', to the release magnet 67, to battery lead 151, thence through battery B and to ground G. The release magnet 67 upon energizing releases 120 125 the connector switch-shaft and restores the 128

connector side switch to its first position, returning the vertical magnet 63 to the control of the vertical relay 61. Therefore, if the calling subscriber (Fig. 7) presses the 5 signaling button 28 and grounds the vertical line conductor 145, he operates the vertical line relay 61, which latter in turn operates the vertical magnet 63. The vertical magnet armature raises the switch-shaft so that 10 the normal post arm 81 permits the switch-shaft spring 82 to come into contact with the spring 80, and the busy signaling current is sent to the calling subscriber's station. The calling subscriber, upon hearing the busy 15 signal, will understand that the desired line is in service, and will release the switch-shaft apparatus over the same circuits previously described by hanging up his receiver. Suppose now that subscriber #1, 20 for instance, desires connection with substation #5; the former on removing the receiver 217 from the switch-hook 220 is connected with the master substation over the following circuit: from receiver 217 to the 25 rotary line conductor 218, springs 93 and 92, springs 189' and 198, condenser 143, conductor 197, receiver 196, secondary winding 194 of the coil 195 to the push-button spring 193, springs 192 and 191, conductor 190, 30 condenser 144, springs 189 and 198', springs 89 and 90, conductor 212, springs 213 and 214, push-button spring 215, winding 216, thence to the receiver 217. He presses the 35 signaling button 234, which closes an energizing circuit through the winding 131 of the buzzer relay 130. The buzzer relay 130 upon energization attracts its armature 132, which causes the springs 133 and 134 to disengage, thereby breaking the energizing 40 circuit through the winding 131 and de-energizing the relay. The relay upon de-energizing permits the springs 133 and 134 to again engage, and again complete the energizing circuit through the winding 131. 45 This intermittent energization of the relay 130 continues as long as the spring 215 is held in contact with the point 235. The operator at the master telephone upon hearing the buzzing signal removes the receiver 196 and learns that connection with the substation #5 is desired. The master telephone subscriber then simultaneously presses the lock-in push-button 139 of line #1 and the 50 corresponding button of line #5, thus simultaneously energizing the locking relays 83 and 87 with the locking magnet 98, and locking the lines #1 and #5 in on the line #220. The energizing circuit for relay 83 extends from ground "G" through the 55 push-button springs 204 and 205, conductor 206 to the locking relay 83, locking magnet 98, springs 207 and 208, springs 209 and 210, release magnet springs 112 and 111 to the battery lead 203, thence through battery 60 B' to ground g'. The relay 87 is energized 65 over a similar circuit. After connecting the lines, as described, the operator presses the signaling button of line #5, which closes an energizing circuit through the bell or buzzer at substation #5. The master 70 telephone subscriber, by operating the key 135, may listen-in to tell when the subscriber at substation #5 answers. The two sub-stations thus locked in on the main line are free from molestation by any local subscriber, except the master telephone subscriber. The master telephone attendant may, of course, if he wishes to insure against any one else seizing the line while the two local lines are being locked, depress the 75 key 136 and break the energizing circuit for the locking magnet 98. Then, after the button 139 of line #1 and the corresponding button of line #5 are depressed, if key 136 is released the relays 83 and 87 80 are sure to lock-in the connection, as explained; or the operator's key may be used in the same way, since the circuit of the locking magnet 98 is controlled by the springs 207 and 208, as shown. When two 85 subscribers are locked in on the main line, provision must be made to prevent a subscriber who is calling from the main exchange from coming in on the said line. This is done by the called local subscriber 90 when he answers the calling local subscriber. That is, the called local subscriber is instructed that upon answering he must press his signaling button, which grounds the vertical side of his line, as is well known; and since his line is now locked in on the main line, the grounding of the vertical line conductor causes the selector shaft allotted to the main line to be raised from normal, whereby the said main line is made busy to 95 all subscribers of the main exchange. Either subscriber #1 or #5, by hanging up his receiver, may release the first-selector and restore the lock-out switch mechanism, as previously explained, since on so doing he grounds both sides of the trunk line in series 100 with the lock-out switch release relay 127. 105

It will be seen that the lock-out switch, as disclosed, affords means for varied substation connections. When a party desires 115 to call out to the main exchange he removes the receiver from the hook and makes a call in the usual way. The substation is thereby connected to the trunk-line, and all other party line substations are automatically 120 locked out. Replacing the receiver releases the connection in the exchange and releases the mechanism of the lock-out switch. An incoming call is received by the master substation, but any substation having connection with the lock-out switch may be locked-in on the trunk line and thus receive a call direct. In this case the signaling current 125 would pass through the lock-out switch to the ringer and condenser of the locked-in

substation. Connection between any two substations may be made. If it is desired to avoid the help of an operator for inter-communicating calls, a regular buzzer circuit independent of the lock-out switch may be installed between the different substations. The relays and magnets may be of any suitable resistance, but good results have been obtained when the lock-in relays 5 83, 84, 85, 86, 87 and 88 and the lock-in magnet 98 are wound to a resistance of eight ohms; the windings of the differential relay 130 to a resistance of five hundred ohms; and the release relay 127 to a resistance of 10 eighteen ohms.

The connectors and the second or third selectors, if any are necessary, can be arranged on a percentage basis, and can thus be less in number than the subscribers. The 15 first-selectors can also be employed on a percentage basis, in any suitable or known manner. In this way automatic trunking is afforded between lines on which the extension telephones thereof have provisions for inter-communicating and for calling the master 20 telephone.

What we claim as our invention is:—

1. In a telephone exchange system, the combination of automatic means for trunking between calling and called telephone lines, a telephone line provided with a master telephone and several extension telephones, means by which the said automatic trunking means can be controlled from the master telephone or any of said extension telephones, means for enabling any extension telephone to call the master telephone, and means at the master telephone for establishing connection between any two extension telephones.

2. In a telephone exchange system, the combination of automatic means for trunking calling telephone lines into connection with called lines, a master telephone, a plurality of extension telephones, means controlled at the extension telephones for calling the master telephone, and means at each of said telephones for controlling said automatic trunking means.

3. In a telephone exchange system, the combination of automatic means for trunking between subscribers' stations, a master telephone, a plurality of extension telephones, means at the master telephone for connecting together any two extension telephones, and means at the extension telephones for controlling said automatic trunking means.

4. In a telephone exchange system, the combination of automatic means for trunking between subscribers' stations, a master telephone, a plurality of extension telephones, means at the master telephone for connecting together any two extension telephones, and means at the master telephone

for controlling said automatic trunking means.

5. In a telephone exchange system, the combination of automatic means for trunking between subscribers' stations, a master 70 telephone, a plurality of extension telephones, means at the master telephone for connecting together any two extension telephones, and means at the master and extension telephones for controlling said automatic trunking means.

6. In a telephone exchange system, the combination of automatic means for trunking between calling and called telephone lines, a telephone line provided with a master telephone and several extension telephones, means by which the said automatic trunking means can be controlled from the master telephone or any of said extension telephones, means for enabling any extension 85 telephone to call the master telephone, means at the master telephone for establishing connection between any two extension telephones, and means by which the use of one extension telephone renders all other extension 90 telephones inoperative for calling.

7. In a telephone exchange system, the combination of automatic means for trunking calling telephone lines into connection with called lines, a master telephone, a plurality of extension telephones, means controlled at the extension telephones for calling the master telephone, means at each of said telephones for controlling said automatic trunking means, and means by 100 which the use of one extension telephone renders all other extension telephones inoperative for calling.

8. In a telephone exchange system, the combination of automatic means for trunking between subscribers' stations, a master telephone, a plurality of extension telephones, means at the master telephone for connecting together any two extension telephones, means at the extension telephones 110 for controlling said automatic trunking means, and means by which the use of one extension telephone renders all other extension telephones inoperative for calling.

9. In a telephone exchange system, the combination of automatic means for trunking between subscribers' stations, a master telephone, a plurality of extension telephones, means at the master telephone for connecting together any two extension telephones, means at the master telephone for controlling said automatic trunking means, and means by which the use of one extension telephone renders all other extension 120 telephones inoperative for calling.

10. In a telephone exchange system, the combination of automatic means for trunking between subscribers' stations, a master telephone, a plurality of extension telephones, means at the master telephone for 130

connecting together any two extension telephones, means at the master and extension telephones for controlling said automatic trunking means, and means by which the 5 use of one extension telephone renders all other extension telephones inoperative for calling.

11. In a telephone exchange system, the combination of automatic means for trunking between calling and called telephone lines, a telephone line provided with a master telephone and several extension telephones, means by which the said automatic trunking means can be controlled from the 10 master telephone or any of said extension telephones, means for enabling any extension telephone to call the master telephone, means at the master telephone for establishing connection between any two extension 15 telephones, and means by which the use of one extension telephone renders all other extension telephones inoperative for receiving calls.

12. In a telephone exchange system, the 20 combination of automatic means for trunking calling telephone lines into connection with called lines, a master telephone, a plurality of extension telephones, means controlled at the extension telephones for calling the master telephone, means at each of 25 said telephones for controlling said automatic trunking means, and means by which the use of one extension telephone renders all other extension telephones inoperative 30 for receiving calls.

13. In a telephone exchange system, the 35 combination of automatic means for trunking between subscribers' stations, a master telephone, a plurality of extension telephones, means at the master telephone for connecting together any two extension telephones, means at the extension telephones for controlling said automatic trunking 40 means, and means by which the use of one extension telephone renders all other extension telephones inoperative for receiving calls.

14. In a telephone exchange system, the 50 combination of automatic means for trunking between subscribers' stations, a master telephone, a plurality of extension telephones, means at the master telephone for connecting together any two extension telephones, means at the master telephone for 55 controlling said automatic trunking means, and means by which the use of one extension telephone renders all other extension telephones inoperative for receiving calls.

15. In a telephone exchange system, the 60 combination of automatic means for trunking between subscribers' stations, a master telephone, a plurality of extension telephones, means at the master telephone for connecting together any two extension tele-

phones, means at the master and extension 65 telephones for controlling said automatic trunking means, and means by which the use of one extension telephone renders all other extension telephones inoperative for receiving calls.

16. In a telephone exchange system, the combination of automatic connectors for use between calling and called telephone lines, a telephone line provided with a master telephone and several extension telephones, 70 means by which the said automatic connectors can be controlled from the master telephone or any of said extension telephones, means for enabling any extension telephone to call the master telephone, and means at 75 the master telephone for establishing connection between any two extension telephones.

17. In a telephone exchange system, the combination of automatic connectors between calling and called telephone lines, a master telephone, a plurality of extension 80 telephones, means controlled at the extension telephones for calling the master telephone, and means at each of said telephones for 85 controlling said automatic connectors.

18. In a telephone exchange system, the combination of automatic connectors between subscribers' stations, a master telephone, a plurality of extension telephones, 90 means at the master telephone for connecting together any two extension telephones, and means at the extension telephones for controlling said automatic connectors.

19. In a telephone exchange system, the combination of automatic connectors between subscribers' stations, a master telephone, a plurality of extension telephones, means at the master telephone for connecting together any two extension telephones, 105 and means at the master telephone for controlling said automatic connectors.

20. In a telephone exchange system, the combination of automatic connectors between subscribers' stations, a master telephone, a plurality of extension telephones, means at the master telephone for connecting together any two extension telephones, 110 and means at the master and extension telephones for controlling said automatic connectors.

21. In a telephone exchange system, the combination of automatic connectors between calling and called telephone lines, a telephone line provided with a master telephone and 115 several extension telephones, means by which the said automatic connectors can be controlled from the master telephone or any of said extension telephones, means for enabling any extension telephone to call the master 120 telephone, means at the master telephone for establishing connection between any two extension telephones, and means by which

the use of one extension telephone renders all other extension telephones inoperative for calling.

22. In a telephone exchange system, the combination of automatic connectors between calling and called telephone lines, a master telephone, a plurality of extension telephones, means controlled at the extension telephones for calling the master telephone, means at each of said telephones for controlling said automatic connectors, and means by which the use of one extension telephone renders all other extension telephones inoperative for calling.
23. In a telephone exchange system, the combination of automatic connectors between subscribers' stations, a master telephone, a plurality of extension telephones, means at the master telephone for connecting together any two extension telephones, means at the extension telephones for controlling said automatic connectors, and means by which the use of one extension telephone renders all other extension telephones inoperative for calling.

24. In a telephone exchange system, the combination of automatic connectors between subscribers' stations, a master telephone, a plurality of extension telephones, means at the master telephone for connecting together any two extension telephones, means at the master telephone for controlling said automatic connectors, and means by which the use of one extension telephone renders all other extension telephones inoperative for calling.

25. In a telephone exchange system, the combination of automatic connectors between subscribers' stations, a master telephone, a plurality of extension telephones, means at the master telephone for connecting together any two extension telephones, means at the master and extension telephones for controlling said automatic connectors, and means by which the use of one extension telephone renders all other extension telephones inoperative for calling.

26. In a telephone exchange system, the combination of automatic connectors between calling and called telephone lines, a telephone line provided with a master telephone and several extension telephones, means by which the said automatic connectors can be controlled from the master telephone or any of said extension telephones, means for enabling any extension telephone to call the master telephone, means at the master telephone for establishing connection between any two extension telephones, and means by which the use of one extension telephone renders all other extension telephones inoperative for receiving calls.

27. In a telephone exchange system, the combination of automatic connectors be-

tween calling and called telephone lines, a master telephone, a plurality of extension telephones, means controlled at the extension telephones for calling the master telephone, means at each of said telephones for controlling said automatic connectors, and means by which the use of one extension telephone renders all other extension telephones inoperative for receiving calls.

28. In a telephone exchange system, the combination of automatic connectors between subscribers' stations, a master telephone, a plurality of extension telephones, means at the master telephone for connecting together any two extension telephones, means at the extension telephones for controlling said automatic connectors, and means by which the use of one extension telephone renders all other extension telephones inoperative for receiving calls.

29. In a telephone exchange system, the combination of automatic connectors between subscribers' stations, a master telephone, a plurality of extension telephones, means at the master telephone for connecting together any two extension telephones, means at the master telephone for controlling said automatic connectors, and means by which the use of one extension telephone renders all other extension telephones inoperative for receiving calls.

30. In a telephone exchange system, the combination of automatic connectors between subscribers' stations, a master telephone, a plurality of extension telephones, means at the master telephone for connecting together any two extension telephones, means at the master and extension telephones for controlling said automatic connectors, and means by which the use of one extension telephone renders all other extension telephones inoperative for receiving calls.

31. In a telephone system, the combination of a line, a master telephone and a plurality of extension telephones on said line, a signaling key-switch for each extension, a locking-in key-switch for each extension, automatic means for locking out the extensions not locked-in on the line, a special key-switch for releasing the extensions from the line, and a key-switch for connecting the master telephone with the line.

32. In a telephone system, the combination of a line, a master telephone and a plurality of extension telephones on said line, a signaling key-switch for each extension, a locking-in key-switch for each extension, automatic means for locking out the extensions not locked-in on the line, a special key-switch for releasing the extensions from the line, a key-switch for connecting the master telephone with the line, and automatic means for restoring the lock-out box to normal by the hanging up of an extension telephone.

33. In a telephone exchange system, the combination of automatic means for trunking between calling and called telephone lines, a telephone line provided with a master telephone and several extension telephones, means by which the said automatic trunking means can be controlled from the master telephone or any of said extension telephones, means for enabling any extension telephone to call the master telephone, means at the master telephone for establishing connection between any two extension telephones, and automatic means for restoring normal relation between all telephone extensions by the hanging up of an extension telephone.

34. In a telephone exchange system, the combination of automatic means for trunking calling telephone lines into connection with called lines, a master telephone, a plurality of extension telephones, means controlled at the extension telephones for calling the master telephone, means at each of said telephones for controlling said automatic trunking means, and automatic means for restoring normal relation between all telephone extensions by the hanging up of an extension telephone.

35. In a telephone exchange system, the combination of automatic means for trunking between subscribers' stations, a master telephone, a plurality of extension telephones, means at the master telephone for connecting together any two extension telephones, means at the extension telephones for controlling said automatic trunking means, and automatic means for restoring normal relation between all telephone extensions by the hanging up of an extension telephone.

36. In a telephone exchange system, the combination of automatic means for trunking between subscribers' stations, a master telephone, a plurality of extension telephones, means at the master telephone for connecting together any two extension telephones, means at the master telephone for controlling said automatic trunking means, and automatic means for restoring normal relation between all telephone extensions by the hanging up of an extension telephone.

37. In a telephone exchange system, the combination of automatic means for trunking between subscribers' stations, a master telephone, a plurality of extension telephones, means at the master telephone for connecting together any two extension telephones, means at the master and extension telephones for controlling said automatic trunking means, and automatic means for restoring normal relation between all telephone extensions by the hanging up of an extension telephone.

38. In a telephone exchange system, the combination of automatic means for trunk-

ing between calling and called telephone lines, a telephone line provided with a master telephone and several extension telephones, means by which the said automatic trunking means can be controlled from the master telephone or any of said extension telephones, means for enabling any extension telephone to call the master telephone, means at the master telephone for establishing connection between any two extension telephones, and automatic means for restoring normal relation between all telephone extensions by the hanging up of an extension telephone.

39. In a telephone exchange system, the combination of automatic means for trunking calling telephone lines into connection with called lines, a master telephone, a plurality of extension telephones, means controlled at the extension telephones for calling the master telephone, means at each of said telephones for controlling said automatic trunking means, means by which the use of one extension telephone renders all other extension telephones inoperative for calling, and automatic means for restoring normal relation between all telephone extensions by the hanging up of an extension telephone.

40. In a telephone exchange system, the combination of automatic means for trunking between subscribers' stations, a master telephone, a plurality of extension telephones, means at the master telephone for connecting together any two extension telephones, means at the extension telephones for controlling said automatic trunking means, means by which the use of one extension telephone renders all other extension telephones inoperative for calling, and automatic means for restoring normal relation between all telephone extensions by the hanging up of an extension telephone.

41. In a telephone exchange system, the combination of automatic means for trunking between subscribers' stations, a master telephone, a plurality of extension telephones, means at the master telephone for connecting together any two extension telephones, means at the master telephone for controlling said automatic trunking means, means by which the use of one extension telephone renders all other extension telephones inoperative for calling, and automatic means for restoring normal relation between all telephone extensions by the hanging up of an extension telephone.

42. In a telephone exchange system, the combination of automatic means for trunking between subscribers' stations, a master telephone, a plurality of extension telephones, means at the master telephone for connecting together any two extension tele-

phones, means at the master and extension telephones for controlling said automatic trunking means, means by which the use of one extension telephone renders all other 5 extension telephones inoperative for calling, and automatic means for restoring normal relation between all telephone extensions by the hanging up of an extension telephone.

43. A subscriber's line, a lock-out box, a 10 release relay therefor, and means for grounding both sides of the line through the coil of said relay.

44. A subscriber's line, a buzzer relay having differential windings normally bridged 15 across the line, and means for grounding one side of the line to energize said relay, the differential preventing energizing of the relay when both sides of the line are grounded.

45. A telephone system comprising an extension telephone lock-out box provided with a locking magnet, a circuit for said magnet, another magnet having an armature mechanically controlled by said locking magnet, a 20 key-switch controlling said circuit, and a second key-switch also controlling said circuit.

46. An extension telephone system comprising means at the master telephone for supervising all connections between an extension telephone and any other telephone, 30 automatic means for trunking calling subscribers into connection with called subscribers, and means at the extension and master telephones for controlling said trunking means.

47. A telephone system comprising a master telephone, line extensions extending therefrom, an extension telephone lock-out box provided with relays for connecting the 40 extensions with the main line, which main line leads to a central station, and signals operated by said relays, connected with the master telephone.

48. In a telephone system, the combination 45 of a subscriber's line, a plurality of telephones connected therewith, an electromagnetically-controlled lock-out mechanism adapted automatically to disconnect all of the telephones from the line except the one in use, a source of current for operating 50 said lock-out mechanism, the combination thus set forth including provisions for permitting intercommunication between any two of the different subscribers to whom the line is common, a second subscriber's line, and means including automatic switches for extending a connection from one line to the other.

49. In an apparatus of the character specified, the combination with a line circuit and a plurality of subscribers' station circuits connected in multiple therewith, of means common to all said station circuits and operated from a subscriber's station for automatically cutting the remaining station cir-

cuits out of the line circuit, and means at a certain one of said stations, which station is provided with a master telephone, for controlling disconnection between any two substations on the same line.

50. In apparatus of the character specified, the combination with a line circuit and a plurality of subscribers' station circuits connected in multiple with the line circuit, of means common to all of said station circuits and operated from a subscriber's station when the circuit is closed through any one of the station circuits for automatically cutting the remaining station circuits out of the line circuit, and means at a certain one 70 of said stations, which station is provided with a master telephone, for controlling disconnection between any two substations on the same line.

51. An extension telephone system provided with master and extension telephones, means at one telephone for controlling disconnection between two other telephones on the same line, and an automatic switch for finding the line of said telephones.

52. In an extension telephone system, a master telephone provided with means controlling disconnection between the extensions thereof, and an automatic switch for finding the line of said telephones.

53. In a telephone exchange system, the combination of automatic means for trunking calling telephone lines into connection with called lines, a master telephone, an extension telephone, means controlled at the 100 extension telephone for calling the master telephone, and means at each of said telephones for controlling said automatic trunking means.

54. In a telephone system, the combination of a subscriber's line, telephones connected therewith, an electromagnetically-controlled lock-out mechanism adapted to automatically disconnect one telephone from the line when the other is in use, a source of 105 current for operating said lock-out mechanism, the combination thus set forth including provisions for permitting intercommunication between the different subscribers to whom the line is common, a second subscriber's line, and means including automatic switches for extending a connection from one line to the other.

55. In a telephone system, the combination of a subscriber's line, telephones connected with said line, an electromagnetically-controlled lock-out mechanism associated with one of said telephones and adapted to automatically disconnect one telephone when the other is in use, a source 125 of current for operating said lock-out mechanism, the combination thus set forth including provisions for permitting intercommunication between the different subscribers to whom the line is common, a second sub- 130

scriber's line, and means including automatic switches for extending a connection from one line to the other.

56. In a telephone system, a plurality of subscribers' lines, a manual operator's board, automatic means for extending connection from one of said lines to said board, manual means controlled by said operator for extending the connection to the other of said lines, and automatic means under the control of either of said subscribers for releasing said connection.

57. In a telephone system, a manual operator's board, means for extending connection to said board, means controlled by said operator for connecting with a called line, and automatic means controlled from said called line for releasing said connection.

58. In a telephone system, a manual operator's board, means including automatic switches for extending connection to said board, a key-switch on said board for ex-

tending said connection to a called subscriber's line, and automatic means controlled by said subscriber for releasing said connection independently of an operator.

59. In a telephone system, a line circuit, a plurality of subscribers' station circuits connected in multiple therewith, means common to all of said station circuits and operated from a subscriber's station for automatically cutting the remaining station circuits out of the line circuit, a master telephone at one of said stations, and means at said master telephone station for controlling the disconnection between any two substations on the same line.

Signed by us at Chicago, Cook county, Illinois, this 14th day of December, 1906.

TALBOT G. MARTIN.
FRITZ LUBBERGER.

Witnesses:

EDWARD D. FALER,
ARTHUR B. SPERRY.

Copies of this patent may be obtained for five cents each, by addressing the "Commissioner of Patents, Washington, D. C."

It is hereby certified that in Letters Patent No. 1,151,547, granted August 24, 1915, upon the application of Talbot G. Martin and Fritz Lubberger, of Chicago, Illinois, for an improvement in "Automatic Extension Telephone Systems," errors appear in the printed specification requiring correction as follows: Page 7, line 45, for the word "locking" read *lock-in*; page 8, line 18, after the word "release" insert the word *relay*; page 9, line 117, for the reference-numeral "228" read 228'; and that the said Letters Patent should be read with these corrections therein that the same may conform to the record of the case in the Patent Office.

Signed and sealed this 11th day of January, A. D., 1916.

J. T. NEWTON,

Acting Commissioner of Patents.
